OBSERVATION TOWER

Robert E. Rasche, 6585 N. River Road, Glendale, Wis.

Filed Jan. 30, 1964, Ser. No. 78,425

Term of patent 14 years

(Cl. D13—1)

FIG. 1

I claim:

The ornamental design for an observation tower, substantially as shown.
